UNITED STATES PATENT OFFICE.

JOHN A. HOWARD, SR., OF WEST NEW BRIGHTON, NEW YORK, ASSIGNOR OF ONE-HALF TO SAMUEL T. SHAW, JR., OF NEW YORK, N. Y.

SECTIONAL BOILER.

1,411,101.

Specification of Letters Patent. Patented Mar. 28, 1922.

Application filed November 11, 1919. Serial No. 337,122.

To all whom it may concern:

Be it known that I, JOHN A. HOWARD, Sr., a citizen of the United States, and a resident of West New Brighton, in the county 5 of Richmond, Staten Island, and State of New York, have invented a certain new and useful Improvement in a Sectional Boiler, of which the following is a full, clear, and exact specification.

10 This invention relates more particularly to a class of heating apparatus.

My invention has for its object primarily to provide a boiler designed to be employed for heating buildings and other structures 15 by either steam or hot water, and which is of a sectional type so that additions may be made thereto for increasing the supply of units of heat when an increased radiation is desired without requiring the boiler to be replaced with a new one as well as permitting 20 repairs to parts of the boiler to be made in event of damage by wear or otherwise without removal of the boiler in entirety. These advantages are attained mainly by providing 25 a front section, a back section and one or more intermediate sections, each having a main water chamber supported upon spaced walls or standards with a hollow base portion so that when the sections are assembled 30 the spaces between the walls provide a fire box and the hollow base portions provide an ash pit. The main chamber of each section of the boiler has an inlet for admitting water as well as having an outlet, and the 35 outlets of all the sections are connected to a common pipe for delivering the water or steam for heat radiation. Thus in event of needing repairs one or more of the sections of the boiler may be replaced with new ones 40 or other sections may be readily added when it is desired to enlarge the capacity of the boiler.

Another object of the invention is to provide in each section one or more separate inner heating chambers which are removably arranged in the fire box portion of each section, and each inner chamber has a water receiving inlet and an outlet communicating with the inlet of the main chamber for supplying water to the main chamber so that the water previous to its delivery to the main

chamber will be heated whether the fire in the boiler is banked or in active combustion.

Still another object of the invention is to provide on the exterior of each inner heating chamber ribs or corrugations whereby the surface area of the chamber when of a given size is enlarged for hastening the heating of the water and enabling its heat to be maintained at an efficient temperature with 55 a moderate consumption of fuel in the fire box.

A further object of the invention is to provide a simple and durably constructed sectional boiler adapted to be made in any suitable shape and size. 65

With these and other objects in view the invention will be hereinafter more fully described with reference to the accompanying drawings forming a part of this specification in which similar characters of reference 70 indicate corresponding parts in all the views, and will then be pointed out in the claims at the end of the description.

In the drawings, Figure 1 is a fragmentary view, partly broken away, showing a side elevation of one form of sectional boiler embodying my invention. 75

Fig. 2 is a detail sectional view taken on the line 2—2 of Fig. 1. 80

Fig. 3 is a detail sectional view taken on the line 3—3 of Fig. 1.

Fig. 4 is an enlarged elevation, partly fragmentary, of one of the superheating chambers employed in the boiler, and 85

Fig. 5 is a sectional view, partly in detail, taken on the line 5—5 of Fig. 4.

The boiler or heating apparatus has a front section 10, a back section 11 and between these sections may be provided one or 90 a number of intermediate sections, as 13, according to the desired capacity of the boiler. All of these sections are preferably of corresponding sizes and shapes, and each section has a hollow body part 14 providing 95 a main chamber which may be of any suitable shape, though the form illustrated is somewhat oval or elliptic in cross section. The main chamber 14 of each of the sections is supported upon two spaced side walls or 100 standards 15 and 16 which are disposed downwardly from the main chamber so that

the narrow curved parts of the chamber are disposed on a longitudinal plane, and when each section of the boiler is made in the form of a metallic shell the side walls of 5 each section may be hollow, as shown. On the lower ends of the side walls 15 and 16 of each section may be provided a hollow base portion 17, and the spaces between the side walls provide a fire box 18, while the 10 interior of the base portions provide an ash pit 19 when the front 10 and back 11 sections are assembled to provide a boiler complete or when one or more of the intermediate sections 13 are employed to provide the 15 boiler, the required arrangement of the sections consisting of disposing the sections in adjoining positions so that the spaces between the side walls are in register and the interior of the base portions are in communication. The space between the side walls 15 and 16 at the exposed face of the front section 10 of the boiler is closed by a wall 20 with a door, as 21, leading into the fire box 18, and the hollow base portion 17 20 of the front section has a front wall 22 with a door 23 leading into the ash pit 19. The space between the side walls 15 and 16 at the exposed face of the back section 11 of the boiler may be closed by a wall 23^a and 25 the hollow base portion 17 of the back section 30 may terminate with a wall 24.

The fire box portion and the interior or ash pit portion of each section of the boiler are in communication, and crosswise of the 35 lower part of the fire box portion of each section is a grate, as 25. On opposite parts of the grate 25 of each section of the boiler are protruding studs 26 and 27 which are rotatably mounted in sockets on the interior 40 of the side walls 15 and 16 of the fire box portion of each section, and at one of the corresponding studs of all of the grates is a depending arm, as 27^a. The grates are thereby adapted to be tilted to allow the 45 ashes of the burned fuel to be shaken from the fire box into the ash pit, and to permit all of the grates of the boiler to be operated in unison for sifting the ashes the depending arms 27^a of the grates are pivoted to a 50 common longitudinally disposed bar 28 which extends to the front section 10. To this end of the operating bar 28 is pivoted, at 29, the lower end of an upwardly disposed handle 30 having its central part pivoted, at 55 31, to the front section of the boiler so that by swinging the upper part of the handle accordingly the bar 28 will be moved back and forth for tilting the grates to sift the ashes from the fire box into the ash pit of 60 the boiler.

In corresponding parts of the front section, back section and each of the intermediate sections of the boiler may be one or two inlets 32 and 33 both of which lead

into the main chamber 14 of the respective 65 section for admitting water into the main chambers. In similar parts of the tops of the sections of the boiler is an outlet 34 for discharge of steam or water from the main chamber of each section according to 70 whether the boiler is used as a hot water or steam heating apparatus. On the main chamber of the front section, back section and each of the intermediate sections of the boiler may be provided a safety valve 35, a 75 steam gage 36 and a water gage 37 all of which may be of any well known or preferred types.

In order to heat the water before its delivery to the main chamber 14 of each section of the boiler in the fire box portion 18 of the front section 10, back section 11 and each intermediate section 13 are provided one or two separate inner heating chambers, as 38 and 39. All of these superheating chambers are preferably of like formations, and each chamber has an elongated hollow body, as 40, with corrugations or spaced ribs 41 on its entire exterior so that the chambers when of given sizes will be 90 provided with enlarged surface areas for receiving an unusual spread of heat from the burning fuel in the fire box of the boiler. The inner heating chambers may be disposed longitudinally or in any suitable positions in the fire box portions of the sections of the boiler, but I prefer to arrange the chambers in vertical positions adjacent to the side walls of the sections, as shown, as well as disposing the chambers so that their 100 lower ends will be in spaced proximity to the grate 25, in order that the chambers will be subjected to the direct heat of the burning fuel whether the fire is banked or in a state of active combustion. The pair 105 of the inner heating chambers of each section of the boiler has in their lower end parts inlet pipes 41 and 42 which pass through openings in the contiguous side walls of the section. When the sections 110 of the boiler are assembled all of the inlet pipes 41 are connected to a common pipe, as 43, leading from a suitable source of water supply with a valve 44 interposed therein for cutting off the supply when needed, 115 while the inlet pipes 42 are likewise connected to a common pipe, as 44, also leading from the source of water supply, and if desired in the supply pipe 44 may be interposed a cut-off valve, not shown. Leading 120 from the upper end parts of the inner heating chambers of each section of the boiler are outlet pipes 45 and 46 both of which are connected to the inlets 32 and 33 of the main chamber 14 of their section 125 of the boiler so that water, as 47, delivered into each pair of the heating chambers will after being heated flow through each pair

of the outlet pipes into the main chamber. In the back section 11 of the boiler and leading from its fire box is a chimney or smoke flue 48, and the outlet 34 of the 5 main chamber of each section of the boiler is connected to a common pipe 49 for distributing the steam to radiators, not shown, for heating purposes. Thus I provide a boiler of a simple, durable and unusually 10 efficient construction for heating buildings and other structures, and which is of a sectional form whereby increased units of heat when desired may be provided by enlarging the boiler with additional sections 15 as well as allowing repairs to parts of the boiler to be made in event of damage by wear or otherwise.

In the foregoing description, I have embodied the preferred form of my invention, but I do not wish to be understood 20 as limiting myself thereto, as I am aware that modifications may be made therein without departing from the principle or sacrificing any of the advantages of this invention, therefore, I reserve to myself the 25 right to make such changes as fairly fall within the scope thereof.

Having thus described my invention, I claim as new and desire to secure by Letters 30 Patent:—

1. The combination, in a boiler, of a front section and a back section, each having a main water chamber supported upon two spaced walls with a hollow base portion so 35 that when arranged whereby the spaces between the walls are in communication a fire box will be provided and the interior of the base portions will provide an ash pit, the main chamber of each section having an inlet and an outlet, the outlets, being relatively arranged so as to be connected to a common distributing pipe, and a pair of removable 40 separate inner heating chambers in the fire box of each section, each of said inner chambers having an inlet leading from a source of water supply and having an outlet leading to the inlet of the main 45 chamber.

2. The combination, in a boiler, of a front 50 section, a back section and an intermediate section, each having a main water chamber supported upon two spaced walls with a hollow base portion so that when arranged whereby the spaces between the walls are in 55 communication a fire box will be provided and the interior of the base portions will provide an ash pit, the front section having a door leading into the fire box as well as having a door leading into the ash pit and the main chamber of each section having an inlet and an outlet, the outlets being relatively arranged so as to be connected to a common distributing pipe, and a pair of removable 60 separate inner heating chambers in

the fire box of each section, each of said 65 inner chambers having an inlet leading from a source of water supply and having an outlet leading to the inlet of the main chamber.

3. The combination, in a boiler, of a front 70 section and a back section, each having a main water chamber supported upon two spaced walls with a hollow base portion so that when arranged whereby the spaces between the walls are in communication a fire 75 box will be provided and the interior of the base portions will provide an ash pit, the main chamber of each section having an inlet and an outlet, a movable grate between the fire box and the ash pit of each section, 80 and a pair of removable separate inner heating chambers in the fire box of each section, each of said inner chambers having an inlet leading from a source of water supply and having an outlet leading to the inlet of the 85 main chamber.

4. The combination, in a boiler, of a front section, a back section and intermediate sections, each having a main water chamber supported upon two spaced walls with a hollow base portion so that when arranged whereby the spaces between the walls are in communication a fire box will be provided and the interior of the base portions will 90 provide an ash pit, the front section having a door leading into the fire box as well as having a door leading into the ash pit and the main chamber of each section having an inlet and an outlet, a movable grate between the fire box and the ash pit of each 95 section, and a pair of removable separate inner heating chambers in the fire box of each section, each of said inner chambers having an inlet leading from a source of water supply and having an outlet leading to the inlet of the main 100 chamber.

5. The combination, in a boiler, of a front section and a back section, each having a main water chamber supported upon two spaced walls with a hollow base portion and the sections being arranged so that the 110 spaces between the walls provide a fire box, the main chamber of each section having an inlet and an outlet, a distributing pipe connecting the outlets, and a pair of removable 115 separate inner heating chambers with corrugated exterior surfaces in the fire box of each section, each of said inner chambers having an inlet leading from a source of water supply and having an outlet leading 120 to the inlet of the main chamber.

6. The combination, in a boiler, of a front section, a back section and intermediate sections, each having a main water chamber supported upon two spaced walls with a hollow base portion and the sections being arranged so that the spaces between the walls provide a fire box, while the interior 125

of the base portions provide an ash pit, the main chamber of each section having an inlet and an outlet, a distributing pipe connecting the outlets, a movable grate between the fire box and the ash pit of each section, and a pair of removable separate inner heating chambers with corrugated exterior surfaces in the fire box of each section, each of said inner chambers having an

inlet leading from a source of water supply 10 and having an outlet leading to the inlet of the main chamber.

This specification signed and witnessed this 10th day of November, A. D. 1919.
